CLAIM

The ornamental design for a hood for gas induction range with oven, as shown and described.

DESCRIPTION

1. Hood for gas induction range with oven
1.1 is a perspective view of a hood for gas induction range with oven when it slides out;
1.2 is a front elevation view thereof;
1.3 is a rear elevation view thereof;
1.4 is a left-side elevation view thereof;
1.5 is a right-side elevation view thereof;
1.6 is a top plan view thereof;
1.7 is a bottom plan view thereof;
1.8 is another perspective view thereof in a use condition;
1.9 is another perspective view with its front cover being opened in a use condition;
1.10 is a perspective view of the hood for gas induction range with oven when it slides in;
1.11 is a front elevation view thereof;
1.12 is a rear elevation view thereof;
1.13 is a left-side elevation view thereof;
1.14 is a right-side elevation view thereof;
1.15 is a top plan view thereof;
1.16 is a bottom plan view thereof; and
1.17 is another perspective view thereof in a use condition.

(Continued)

The broken lines in the drawing figures are included for the purpose of illustrating environment and form no part of the claimed design.
